UNITED STATES PATENT OFFICE.

RICHARD L. FEARN, JR., OF WASHINGTON, DISTRICT OF COLUMBIA, ASSIGNOR TO NATIONAL ELECTRICAL SUPPLY COMPANY, OF WASHINGTON, DISTRICT OF COLUMBIA, A CORPORATION OF VIRGINIA.

PROCESS OF AND APPARATUS FOR PREVENTING OFFSETTING, &c.

1,388,418.

Specification of Letters Patent. Patented Aug. 23, 1921.

Application filed April 5, 1920. Serial No. 371,402.

To all whom it may concern:

Be it known that I, RICHARD L. FEARN, Jr., a citizen of the United States, residing at Washington, in the District of Columbia, have invented certain new and useful Improvements in Processes of and Apparatus for Preventing Offsetting, &c., of which the following is a specification.

This invention relates to a process of and apparatus for preventing off-setting and neutralizing static charges.

The present practice in printing of piling freshly printed sheets of paper one upon another frequently results in a considerable loss of paper, due to the fact that the fresh ink often adheres to the under side of the next sheet above.

In the case of presses adapted for printing on both sides of the paper, the printing operations are accomplished in two steps, each involving passing the paper between a platen roller and a type member. In this case, the side of the paper first printed on is in contact with the second platen roller during the second printing operation, a considerable quantity of fresh ink being deposited thereon. Much time and labor is necessary in order to keep the second platen roller clean, requiring the use of certain expensive oils as solvents for the ink.

It is well known that printers' ink depends upon oxidation in the process of drying and hardening. I have found that the oxidation power of ozone is greatly increased when it is applied in the presence of heat and moisture to the substance to be dried.

An important object of this invention is to provide means for very rapidly drying and hardening the ink by a novel process of oxidation, thus preventing the papers from offsetting when piled one upon another, and also preventing the deposit of ink on the second platen roller.

Another object of the invention is to neutralize the effect of static electricity generated during the printing operation.

Other objects and advantages of the invention will be apparent during the course of the following description.

In the accompanying drawings forming a part of this specification and in which like numerals are employed to designate like parts throughout the same,

Figure 1 is a diagrammatic view of a type of press adapted for printing on both sides of a sheet of paper, illustrating the position of the distributing heads and heating elements with respect thereto,

Fig. 2 is a diagrammatic view of the parts of my invention,

Fig. 3 is a cross-section of the distributing head and heating elements,

Fig. 4 is a plan view of one of the heating elements, parts being broken away for the purpose of illustration, and,

Fig. 5 is a fragmentary perspective of one of the distributor heads.

In the drawings, wherein for the purpose of illustration is shown a preferred embodiment of my invention, the numeral 10 designates the first platen roller and 11 the first printing roller of a press adapted for printing on both sides of a sheet of paper, and 12 and 13 the second platen and print- 70 ing rollers respectively, thereof.

Above the roller 10 at approximately the point at which the incoming paper contacts with the roller, is mounted a distributing head 14, embodying a cylinder 15, provided 80 longitudinally adjacent the surface of the paper with a series of openings 16, for a purpose to be described. Heating elements 17 are mounted at each side of the distributor head 14, as shown. The form of heat- 85

ing elements which I prefer to employ comprises layers of insulation 18, having electric resistance wires 19, interposed therebetween and connected to a suitable source of current supply. The wires and insulation are inclosed in a metallic casing 20, the upper face 20' of which is highly polished.

A substantially inverted U-shaped reflecting member 21, preferably of bronze, is provided, having its edges 22 clamped about 95 the edges of the casing 20, as shown. The back 23 of the reflecting member is preferably spaced from the casing 20, providing a heat retaining space 23', and has its inner and outer faces 24 and 24' highly polished.

The polished surfaces above referred to serve to retain within the space 23' and reflect heat that would otherwise be lost from the upper side of the heating element. As clearly shown in Fig. 3, the distributor head 100 14 and heating elements 17 are spaced slightly from the paper 25.

A second distributor head 26 and heating

elements 27 are mounted adjacent the paper near the point at which it passes from the second printing roller and platen. Arranged in spaced relation to the paper and 5 on the opposite side therefrom from the head 26 and heating elements 27, I preferably employ a heat reflector 28, to reflect back to the paper any heat that is radiated therethrough. The use of this reflector is 10 desirable, but is not necessary.

Referring to Fig. 2 of the drawings, the numeral 29 designates an ozonizer of any preferred type having an inlet 30, for the air, and a conduit 31 leading therefrom and 15 adapted to carry the ozonized air to a blower 32. The blower 32 is provided with a conduit 33, passing into a humidifier 34, containing water, steam, alcohol, ammonia, or other volatile liquids or moist fluids. The 20 conduit 33 has its end 35 turned downwardly, and if the humidifying agent is used in liquid form, the end 35 extends below the surface of the liquid. A heater 34' preferably made up of heating elements similar to 25 the heating elements 17, is disposed beneath the humidifier 34 to maintain the fluid therein at an elevated temperature.

An outlet pipe 36 is connected to the top of the humidifier 34 and connects with 30 branch pipes 37 which carry the ozone into distributor heads 14 and 26, from which it is distributed across the surface of the paper 25 through the openings 16.

In my apparatus, the ozone generated in 35 the ozonizer 29 is blown out by the blower 32, passing into the humidifier 34 and through the humidifying agent therein. This agent is maintained at a relatively high temperature by the heater 34'. When water 40 is used as the humidifying agent, I prefer to maintain it at a temperature of about 160° F. More volatile liquids are maintained at a lower temperature. The ozonized air takes up a considerable amount of 45 moisture, due to the elevated temperature of the humidifier, this temperature being sufficiently high to assist in the volatilization of the fluid and to maintain the humidified ozonized air in a heated condition until its 50 delivery upon the surface of the paper through the pipes 36 and 37, and the distributor openings 16.

The elevated temperature of the ozonized air and the rapidity of the process of oxidation 55 permit the use of different grades of ink whose use would otherwise not be possible, the heat serving to soften the thicker grades of ink and the rapid oxidation preventing the spreading of the ink upon the surface 60 of the paper. Thus, a more sharply defined print is obtained.

In Fig. 1, the direction of travel of the paper is indicated by the arrows. It will thus be noted, in connection with the platen 65 10, that the ozonized air and heat will be

applied to the surface of the paper, as the paper is fed to the roller and also after having passed around the roller. Thus, it will be seen that the ozonized air and heat are applied both before and after printing. 70

The proximity of the heating elements to the platen 10 causes the latter to absorb sufficient heat to assist in maintaining the elevated temperature of the paper until the first printing operation is completed and 75 neutralizing the static charge on the platen roller. The paper passes off the platen to the next platen and printing roller 12 and 13. Thus, the ink on the upper side of the paper will be dry when the paper reaches 80 the roller 13, and no ink will be deposited on the platen. The process neutralizes the charge of static electricity and any static charge which would prevent the printed sheets lying flat, is removed. The distributor 26 and heating elements 27 satisfactorily dry the ink after the second printing operation, so that the papers will not offset when piled upon each other. The reflector 28 serves to prevent the loss of heat 85 on the opposite side of the paper, the heat being reflected back to the paper. The reflectors, 24, 24' and 28, are preferably formed of highly polished bronze or copper. 90

While I have described my process and 95 apparatus in connection with printing presses, I have found their use advantageous in drying various other substances which depend upon oxidation in drying and hardening, such as varnish on furniture, enamel 100 on signs, etc.

I have illustrated the distributor heads in connection with heating elements, but the use of the latter is not essential and a considerable degree of success may be obtained without the use thereof. If desired, the reflector 28 may also be eliminated. 105

It is to be understood that the form of my invention herewith shown and described is to be taken as a preferred example of 110 the same, and that various changes in the shape, size, and arrangement of parts may be resorted to without departing from the spirit of my invention or the scope of the subjoined claims. 115

Having thus described my invention, I claim:

1. The herein described process for preventing off-setting, which consists in subjecting the paper to the action of humidified 120 ozonized air.

2. The herein described process for preventing off-setting, which consists in subjecting the paper to the action of heated humidified ozonized air. 125

3. The herein described process for preventing off-setting, which consists in heating the paper and subjecting it to the action of humidified ozonized air before and after printing thereon. 130

4. The herein described process for preventing off-setting, which consists in heating the paper, subjecting it to the action of ozonized air, and reheating the paper.
5. The combination with a printing press, of an ozonizer, a humidifier connected with said ozonizer, and means for delivering the humidified ozonized air to the paper as it passes through the press.
- 10 6. The combination with a printing press, of an ozonizer, a humidifier connected with said ozonizer, and a distributor head communicating with said humidifier and arranged in proximity to the paper as it passes through the press, said distributor head comprising a casing provided with openings adjacent the paper.
- 15 7. The combination with a printing press having a platen roller, of an ozonizer, a humidifier connected with said ozonizer, a heater arranged in proximity to said humidifier, a distributor head connected with said humidifier and provided with openings, said distributor head being arranged in proximity to the paper as it passes through the press at approximately the
- point where the paper comes in contact with said platen, and heating elements arranged on either side of said distributor head.
8. The combination with a printing press 30 having a platen, of an ozonizer, a humidifier connected with said ozonizer, a heater arranged in proximity to said humidifier, a distributor head connected with said humidifier and provided with openings, said 35 distributor head being arranged in proximity to the paper as it passes through the press at approximately the point where the paper comes in contact with said platen, and heating elements arranged on either side 40 of said distributor head, said heating elements comprising a pair of insulating strips, a resistance wire interposed between said strips, a casing surrounding said strips and said wire, a reflecting member including a back having its edges secured to the edges of said casing, the back of said reflecting member being spaced from said casing and polished.
- 20 25 In testimony whereof I affix my signature.
- RICHARD L. FEARN, JR.
